(57) **CLAIM**

The ornamental design for a mouthpiece, as shown and described.

DESCRIPTION

FIG. 1 is a perspective view of a first embodiment of a mouthpiece showing my new design;

FIG. 2 is a left side view (where the view of the left side is a mirror image of the view of the right side) of the design of FIG. 1;

FIG. 3 is a bottom plan view of the design of FIG. 1;

FIG. 4 is a top plan view of the design of FIG. 1;

FIG. 5 is a front elevational view of the design of FIG. 1; and,

FIG. 6 is a rear elevational view of the design of FIG. 1. The broken lines in the drawings depict portions of the mouthpiece that form no part of the claim.
